(57) **CLAIM**

The ornamental design for a floating canister holder, as shown.

DESCRIPTION

FIG. 1 is a perspective view of a canister; FIG. 2 is a front view of the floating canister holder of FIG. 1;

FIG. 3 is a rear view of the floating canister holder of FIG. 1;

FIG. 4 is a right side view of the floating canister holder of FIG. 1

FIG. 5 is a left side view of the floating canister holder of FIG. 1;

FIG. 6 is a top view of the floating canister holder of FIG. 1; and,

FIG. 7 is a bottom view of the floating canister holder of FIG. 1.

The dashed lines are not part of the design and are included for illustrating the use of the invention.
